UNITED STATES PATENT OFFICE.

HENRY HOWSON, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

PASSENGER-CAR.

No. 901,903.

Specification of Letters Patent.

Patented Oct. 20, 1908.

Application filed May 25, 1908. Serial No. 434,956.

To all whom it may concern:

Be it known that I, HENRY Howson, a citizen of the United States, residing in Philadelphia, Pennsylvania, have invented 5 certain Improvements in Passenger-Cars, of which the following is a specification.

My invention relates to certain improvements in cars of the type in which a passenger pays the fare on entering the car.

10 The object of my present invention is to close one side of the platform by means of doors so arranged that they will not interfere with passengers standing on the platform. The platform is entirely inclosed and 15 the doors are not needed in the transverse partition dividing the platform from the body of the car.

In the accompanying drawings:—Figure 1, is a sectional plan view of one end of a 20 passenger car illustrating my invention, and showing the doors open, leaving a clear space for the ingress and egress of passengers; Fig. 2, is a view similar to Fig. 1, showing the doors closed and seats arranged on both 25 sides of the platform for the accommodation of passengers; this arrangement being used when the platform is at the forward end of the car; and Fig. 3, is a longitudinal sectional view on the line 3—3, Fig. 1.

30 A is the body of the car.

B is the platform separated from the body of the car by a transverse partition C having ingress and egress passageways c, c' separated in the present instance by a central 35 post C'.

B' is the vestibule framework inclosing the front of the car.

At one side of the platform is a fixed panel section B² having a channel b² for the reception 40 of a sliding door E, which is at the forward end of the car and under the control of the motorman. This door closes the passageway b². At the opposite side of the platform adjoining the forward section B' 45 is a panel D having a channel d for a sliding door, and between this panel D and the transverse partition C is a post D' separating the edge of the platform into two passageways b⁴ and b⁵, one for the ingress of 50 passengers and the other for the egress of

passengers, and extending from this post to the center post C' of the transverse partition C is a guard I in the form of a rail. This guard divides the platform into ingress and egress sections b, b'; the ingress section communicating with the passageway c in the partition C and the egress section b' connects with the passageway c'. The guard is arranged so as to fold out of the way when it is desired to give a clear space at each side 60 of the platform.

I' is a post secured to the floor of the platform, and pivoted to the center post of the partition C' is a hinged portion i' which can be either raised and locked, or lowered 65 as shown in Fig. 2, and the section i' of the guard is also hinged to the post and can turn on its pivot from the socket i², so as to rest upon a bracket i³ on the section i, as shown clearly in Fig. 2. By this means the 70 rail can be folded to take up the least amount of space when it is desired to form a passage on each side and when the platform is at the forward end of the car.

F, F' are two sliding doors adapted to 75 close the passageways b⁴, b⁵ on each side of the post D'. The door F is adapted to the channel d in the panel D and the door F' is adapted to the channel a in the panel a' built in the side of the body portion of the 80 car. These two doors may be connected in any suitable manner so that when one is opened or closed the other will open or close with it.

In the drawings I have shown one method 85 of construction by which the doors can be operated in unison. This consists of a bracket f and f' on the doors F and F', respectively, and on the bracket f is a rod f² connected to a chain f³ attached to the other bracket and passing around a fixed wheel 90 on the car frame. Projecting from the other bracket f' is a rod f⁴ connected to a chain f⁵ which is attached to the first mentioned bracket f, and this chain passes 95 around a wheel on the fixed portion of the car and each door has grooved wheels adapted to a rail, so that when one door is moved in one direction the other door will move in the opposite direction. There is a 100

handle *s* on the door *F'* within easy reach of the conductor so that he can operate both doors.

In order to provide additional seats for the passengers at the forward end of the car, I hinge a seat *N* to the partition *C* and arrange it so that it can be turned up into a cavity in the partition, forming a panel. This seat is supported midway by a fixed bracket *n'* projecting from the post *D'*.

N' is a short seat section which is pivoted to the panel *D* and can be raised and supported by pivoted brackets carried by the panel; thus providing a seat from one end 15 of the platform to the other on one side of the car. On the opposite side of the car is a seat *M* made in two sections *M'*, *M*². The section *M'* is hinged at *m* to the partition *C* and the section *M*² is pivoted at *m'* 20 to the section *M'*. The seat is adapted to be folded into a recess in the said partition, forming a panel. These sections are supported on hinged brackets *m*² carried by the panel section *B*² so that when the seats are 25 not in use they can be folded out of the way.

When the platform is at the rear end of the car, as in Fig. 1, the rail is placed as shown, so as to divide the platform into ingress and egress sections *b*, *b'*, and the 30 conductor is located in the egress section *b'*. The doors can be operated by the conductor so as to open or close the passageways *b*⁴, *b*⁵ at the side of the car for the ingress and egress of passengers. The door *E* at the 35 opposite edge of the platform is closed and is preferably locked.

When the platform is at the forward end of the car then the two doors *F*, *F'* are closed and locked and the seat sections *N*, *N'* 40 are moved into position and the sections *M'*, *M*² are also moved into position. The rail is folded as in Fig. 2, so as to give a clear passageway on either side thereof, and the outlet door *E* can be opened and closed 45 by the motorman so as to allow passengers to pass out at the forward end of the car as well as at the rear.

I claim:—

1. The combination in a passenger car, of 50 a body portion, a platform, means for closing one side of the platform, said means consisting of a fixed panel at the outer end of the platform, leaving a passageway, and two sliding doors adapted to move towards 55 and from each other to close the passageway.

2. The combination in a passenger car, of 60 a body portion, a platform, a panel at one side of the platform near the outer end thereof, a post separating the space between the panel and the body of the car into ingress and egress passageways, and sliding doors adapted to move to and from each other and arranged to close the passageways.

3. The combination in a passenger car, of

a body portion, a platform, a panel at one 65 side of the platform, near the outer end thereof, a post separating the space between the panel and the body of the car into ingress and egress passageways, said panel having a channel for the reception of a door, 70 a channel at the side of the body portion of the car for the reception of another door, and two doors adapted to the channels and arranged to close the passageways.

4. The combination in a passenger car, of 75 a body portion, a platform, a transverse partition separating the platform from the body portion, a post in the center of the partition forming ingress and egress passageways, a post at the side of the platform, a post at 80 the point near the center of the platform, a rail dividing the said platform into ingress and egress sections, said rail being collapsible so as to provide a clear passageway on each side of the rail when the platform is 85 at the forward end of the car.

5. The combination in a passenger car, of 90 a body portion, a platform, a transverse partition separating the platform from the body of the car and having a center post in said 95 partition, ingress and egress passageways, a post at the side of the platform, a post near the center of the platform, a guard dividing the platform into ingress and egress sections, said guard consisting of two rail sections, one section being pivoted to the center post and to the post in the center of the transverse partition and so arranged that it can be raised and lowered, the other section being hinged to the center post and pivoted 100 to a socket on the post at the side of the car and adapted to be moved into position alongside the other rail section when lowered, so as to provide a clear space on either side of the platform.

6. The combination in a dividing rail for 105 passenger cars, of two posts, a guard rail section pivoted to the posts and arranged to swing so as to lie either in a horizontal or a vertical plane, a lug on the rail section 110 projecting at one side of the section when the latter is in a vertical plane, and a pivoted rail section mounted on one of the posts and capable of being moved to rest upon said lug.

7. The combination in a passenger car, of 115 a body portion, a recessed transverse partition, a platform beyond the partition, means for closing the side of the platform, a seat made in sections pivoted together and pivoted to the transverse partition, and a bracket for supporting said seat section when extended, the seat section when raised and folded resting in the recess in the transverse partition.

8. The combination in a passenger car, of 120 a platform, a panel and two doors closing one side of the platform, a center post be-

tween the two doors, a bracket on the center post, a seat section hinged to the panel, means for supporting the seat section in its raised position, a pivoted seat section hinged to the body of the car at the end of the platform, the body of the car having a recess for the reception of the said seat section when raised.

In testimony whereof, I have signed my name to this specification, in the presence of 10 two subscribing witnesses.

HENRY HOWSON.
